BOAT STERN AND PROPELLER ASSEMBLY

Hippolyte R. Xiques, New Orleans, La.

Application October 21, 1942, Serial No. 462,848

9 Claims. (Cl. 115—34)

My invention relates to small boats, and has among its objects and advantages the provision of an improved stern construction and propeller assembly so designed as to facilitate placement of the propeller assembly and the motor while the boat is in the water.

In the accompanying drawings:

Figure 1 is a top view of a boat in accordance with my invention.

Figure 2 is a perspective view of the propeller assembly.

Figure 3 is an enlarged sectional view of the stern structure.

Figure 4 is a horizontal sectional view of the stern structure illustrating the manner in which the propeller assembly is first placed in position preparatory to placement of the motor, and

Figure 5 is a plan view of a motor support.

In the embodiment of the invention selected for illustration, the hull 10 may be conventional with the exception of the stern structure 12. An opening 14 is provided in the stern structure for accommodation of the propeller 16.

Figure 2 illustrates a propeller assembly 18 wherein a frame 20 is bolted at 22 to an end wall or heavy plank 24 of T-shaped contour. A depending frame 26 is fixedly attached to the frame 10 and constitutes a support for a shaftlog 28. This shaftlog includes a flange 30 bolted at 32 to the plank 24 and declining downwardly from the plank. A propeller shaft 34, see Figure 3, is rotatably supported in the shaftlog and extends through an opening 36 in the plank 24 and through a collar 38 clamped against the opposite face of the plank 24 by the bolts 32. A flange 40 is formed on the propeller shaft 34 and coacts with the propeller 16 to restrain the shaft from relative longitudinal movement.

In Figure 4, the boat bottom 41 and the spaced and parallel walls 42 of the opening 14 are respectively provided with one horizontal and two vertical ribs 44 against which the plank 24 is clamped. A sealing gasket 46 is interposed between the plank and the three ribs. Each wall 42 is provided with two clamps 48 arranged to press the plank 24 into holding engagement with the ribs 44.

In Figure 4, two vertical and one horizontal ribs 52 are respectively attached to the walls 42 forwardly of the ribs 44 and across the bottom 41. A T-shaped plank 54 is provided for coaction with the ribs 52. This plank is pressed against the ribs 52 by clamps 56 attached to the walls 42. The ribs 52, the temporary wall or plank 54 and the clamps 56 are identical with the

plank 24, the ribs 44 and the clamps 48, respectively.

The motor 58 is mounted on a frame 60 anchored inside the boat and forwardly of the ribs 52. This frame includes hooks 62 engageable over the base flange 64 of the motor. Two screws 66 are threaded through an angle 68 of the frame for engagement with the motor to hold the latter in firm connection with the hooks 62. Figure 3 illustrates the frame 60 as being inclined in such manner as to bring the engine driven shaft 70 in coaxial alignment with the propeller shaft 34.

A sleeve coupling 72 is splined on the propeller shaft 34. The adjacent end of the motor shaft 70 is also grooved so that the coupling may be shifted to the position of Figure 3 to fixedly relate the propeller shaft with the motor shaft. Set screws 74 are threaded through the coupling 72 for respective engagement with the propeller shaft and the engine driven shaft.

In a case where the boat is on the bank of a stream, the plank 54 is securely clamped in the position of Figure 4, to provide a watertight closure. The boat may then be placed in the water preparatory to placement of the propeller assembly. The propeller assembly is then placed in position and made secure by tightening the clamps 48. At this time there will be a small amount of water in the space between the planks 24 and 54. This water may be removed with a pump or allowed to flow into the boat, since the plank 54 is removed as soon as the propeller assembly is made secure. The engine 58 is then placed in position and made secure, after which the coupling 72 is shifted from its position of Figure 4 to that of Figure 3 for operatively connecting the propeller shaft with the engine.

A skeg 76 underlies the propeller 16 and has one end secured to the plank 24 and its other end arranged to support the lower end of a rudder shaft 78 to which the rudder 80 is connected. The shaft 78 extends through an opening 82 in the frame 20 and is provided with a tiller 84 to which a tiller rope 86 is connected.

The stern construction is such as to facilitate placement and removal of the propeller assembly. This may be done while the boat is in the water. The propeller assembly 18 is such that the entire complement of propeller, shaft, rudder and skeg are easily handled and at the same time performing efficient service in operating the boat. The motor base permits quick installation of the motor regardless of its size within the limitations of the boat.

The power developed by the motor is directly

transmitted to the propeller shaft, thereby eliminating the use of gears. The propeller assembly may be removed for inspection or repair without requiring beaching or lifting of the boat out of the water. A four cycle engine can be used, thus giving better performance than a two cycle engine, especially with respect to starting. The motor is located inside the boat and may be protected while in operation by a proper cover. There is no vibration transmitted to the tiller, thus making long trips less tiresome to the operator. The invention is constructed of light weight materials and in several parts so as to be easily transported and handled by one person. Through standardization of the attaching parts, different boats, motors and propeller assemblies can be used.

A bar 68 extends across the frame 20 in engagement with the frame 26 and is hingedly connected at one end with the hull of the boat, as at 90, and its other end is bolted at 92 to the hull. Thus any shock caused through engagement between the skeg 76 and obstructions in the water is transmitted to the hull instead of the propeller assembly alone.

Without further elaboration, the foregoing will so fully explain my invention, that others may, by applying current knowledge, readily adapt the same for use under various conditions of service.

I claim:

1. In a boat, the combination of a stern having an opening, a first wall for temporarily closing said opening, a propeller assembly having a propeller shaft and a second wall constituting a closure for said opening, means for securing said propeller assembly to the stern, a motor having a driven shaft for coaxial alignment with the propeller shaft when said first wall is removed, and

means for connecting the propeller shaft with the driven shaft.

2. The invention described in claim 1 wherein said last mentioned means comprises a coupling having splined connection with the propeller shaft and the driven shaft.

3. The invention described in claim 1 wherein clamp means are provided for detachably connecting said first wall to the stern and in which said first mentioned means include clamps for detachably connecting the second wall with the stern.

4. The invention described in claim 1 wherein said stern is provided with first ribs, clamps attached to the stern for clamping the first wall against said ribs, and second ribs fixed to said stern, said last mentioned means comprising clamps attached to the stern for clamping said second wall to said second ribs.

5. The invention described in claim 1 wherein said propeller assembly includes a skeg and a rudder means.

6. The invention described in claim 1 wherein said propeller shaft declines rearwardly of said stern, and an inclined motor base in said stern for supporting the motor at an angle to bring said driven shaft in coaxial alignment with said propeller shaft.

7. The invention described in claim 1 wherein said propeller assembly includes a shaftlog for the propeller shaft fixedly secured to said second wall.

8. The invention described in claim 1 wherein said stern includes a bottom underlying said first and second walls.

9. The invention described in claim 1 wherein a shock bar is fixed to said stern and lies in engagement with the propeller assembly to transmit shocks to the stern.

HIPPOLYTE R. XIQUES.
